APPARATUS FOR THE CONTROL OF HIGHWAY CROSSING SIGNALS

Henry S. Young, Wilkinsburg, Pa., assignor to
The Union Switch & Signal Company, Swiss-
vale, Pa., a corporation of Pennsylvania

Application August 27, 1936, Serial No. 98,216

11 Claims. (Cl. 246—126)

My invention relates to apparatus controlled by a train approaching a highway crossing for governing the operation of a highway crossing signal.

A feature of my invention is the provision of novel and improved apparatus controlled by a train approaching a highway crossing for preventing a continued operation of a highway crossing signal in the event the train should stop within the control section, and for restarting the operation of the signal when the train resumes its movement. Other features and advantages of my invention will appear as the specification progresses.

I will describe several forms of apparatus embodying my invention, and will then point out the novel features thereof in claims.

Apparatus and circuits controlled by a train for preventing a continued operation of a highway crossing signal in the event a train should stop within the control section for the signal and for restarting the operation when the train resumes its movement are disclosed and claimed in the pending application for United States Letters Patent, Serial No. 58,716, filed January 11, 1936, by James J. Vanhorn for Apparatus for the control of highway crossing signals, and of which application my present application is an improvement.

In the accompanying drawings, Fig. 1 is a diagrammatic view of one form of apparatus embodying my invention, and arranged for a track on which traffic moves in one direction only. Fig. 2 is a diagrammatic view of another form of apparatus for a track on which trains normally move in one direction only, and which apparatus also embodies the invention. Fig. 3 is a diagrammatic view of a modification of the apparatus of Fig. 1, and which is applied to a track where trains are ordinarily required to stop only at certain points. Fig. 4 is a diagrammatic view of apparatus for a railway track on which trains normally move in either direction, and which apparatus also embodies the invention. Figs. 5 and 6 are diagrammatic views of train actuated devices for producing periodic interruptions of a control circuit only when a train is moving, and which devices may be used in the apparatus of Figs. 1, 2, 3, and 4. Figs. 7 and 7a are diagrammatic views of a track instrument effective to detect moving and stationary conditions of a train, and which track instrument may be used as the train actuated device in the apparatus of Figs. 1, 2, 3, and 4.

In each of the several views, like reference characters designate similar parts.

Referring first to Fig. 1, the reference characters 1a and 1b designate the track rails of a stretch of railway over which trains normally move in the direction indicated by an arrow, and which rails are intersected by a highway H. A highway crossing signal S is located at the intersection. This signal S may be any one of several types of highway crossing signals, and, as here shown, is an audible signal in the form of an electric bell. The operation of the signal S is controlled by a relay TER, the arrangement being such that when relay SR is released and its back contact 2 is closed, or when the relay TER is released and its back contact 3 is closed, current is supplied to the signal S over a simple operating circuit including contacts 2 and 3 in parallel and the bell sounds a warning. The track rails 1a and 1b may be included in a track circuit for a wayside signal system, but they need not be, since the apparatus of Fig. 1 is operative independent of any wayside signal system.

A series of train actuated devices A1, A2, A3, A4, and A5 is provided, the individual devices being operatively associated with the track rails at selected points on the side of the highway from which trains approach the intersection when they are moving in the normal direction of traffic. These train actuated devices may take different forms, and are shown conventionally in Fig. 1 for the sake of simplicity. One form for the train actuated devices is the track instrument disclosed diagrammatically in Figs. 7 and 7a. This track instrument comprises a weight member 70 attached to one end of a flexible member 71 which is mounted on the track rail at 72 in any convenient manner. A surface of the weight member 70 is provided with a depression 73. Under normal conditions, that is, when flexible member 71 and weight member 70 are not vibrated, the point of a plunger 74 rests in the depression 73. The plunger 74 is attached to a contact finger 75 which is fixed at 76. A second contact finger 77 is fixed at 80 and is normally in engagement with contact finger 75 to complete a circuit connection therethrough. A stop member 78 limits the movement of contact finger 77. When the track rail is vibrated by the wheels of a train passing the point at which the flexible member 71 is attached to the rail, the flexible member and weight are vibrated but the inertia of the weight makes it slow to follow the vibrations so that the plunger 74 is forced out of the depression 73 and the contact finger 75 is forced to the right as viewed in Fig. 7a to break the engagement with contact finger 77. Thus a train wheel moving over the rail

5 at the point at which the track instrument is attached thereto causes the contact 75-77 to open at least momentarily. When no train is present or when a train is standing and the rail is not vibrated, contact 75-77 is closed. It will be understood, of course, that the parts of the track instrument are properly insulated from each other and are also housed against weather and other outside interferences.

10 Another form of track instruments that may be used as the train actuated device is that disclosed and claimed in a copending United States application for Letters Patent, Serial No. 54,500, filed December 14, 1935, by H. G. Witmer, for Circuit 15 controlling instruments.

15 The essential thing regarding the train actuated devices as far as the present application is concerned is that each device includes a circuit controlling element or contact which assumes an open or non-conducting condition only when a 20 train is moving in the vicinity of the device, but when no train is present or when a train is standing, the circuit controlling element assumes a closed condition in which current readily passes 25 therethrough. For example, the contact 4 of device A1 is normally closed and assumes an open position when a train is moving in the vicinity of the device A1. The train actuated devices of the 30 series are placed close enough together so that a train moving at an appreciable speed passes from the point where it actuates the circuit controlling element of one device to a point where it actuates the circuit controlling element of the next device in something less than a predetermined 35 period of time which period I shall assume for the purpose of illustration to be 5 seconds. The relationship of this predetermined period of time with the rest of the apparatus will be referred to hereinafter. While the series of train 40 actuated devices of Fig. 1 contain but five individual devices, it is to be understood that the series may comprise any desired number. The first device A1 encountered by a train approaching the crossing is located from the highway a distance sufficient so that a desired minimum warning 45 period of the highway crossing signal prior to the arrival of the train at the crossing when the train is moving at the maximum speed is assured. The last device A5 of the series is preferably located adjacent the highway crossing. It 50 is to be pointed out that the track instruments here contemplated for use as train actuated devices are of a type which is not effectively influenced by vibrations transverse to the track rail such as might be caused by a train moving on an 55 adjacent track.

The circuit controlling elements 4, 5, 6, 7, and 8 of the train actuated devices A1, A2, A3, A4, and A5, respectively, are connected in series in a circuit for the control relay SR, the circuit normally including front contact 9 of the relay as will be readily understood by an inspection of Fig. 1. The slow acting relay TER associated with the control relay SR is here shown as a slow pick-up relay. The relay TER is so proportioned and adjusted that its contact arm 10 is moved and breaks engagement with back contact 3 only after the winding of the relay has been energized a predetermined period such as 5 seconds, but that upon deenergization of the winding of the relay, the contact arm 10 immediately drops from whatever position it has been advanced to the position where it engages the back contact 3. Relay TER is provided with a check contact 11-12, the contact finger 11 of which is operatively associated with contact arm 10, as indicated by a dotted line in the drawings. The arrangement is such that contact finger 11 engages the stationary contact finger 12 only when the relay is deenergized and its mechanism is fully released. The 5 check contact 11-12 is interposed in the control circuit of relay SR in parallel with front contact 9, and hence relay SR once deenergized and its front contact 9 opened, it is reenergized only if relay TER is released and check contact 11-12 10 is closed. Relay TER is energized by a simple circuit including front contact 13 of control relay SR.

When a train approaching the highway reaches the location of device A1, the contact 4 15 is actuated at least momentarily to its open position to open the stick circuit of relay SR and relay SR is deenergized and releases to close back contact 2 interposed in the operating circuit of signal S, and signal S is set into operation. The 20 release of relay SR opens front contact 13 interposed in the energizing circuit of relay TER, and this latter relay is released to close back contact 3 and complete the second parallel path of the 25 signal operating circuit. Check contact 11-12 25 is closed also when relay TER is deenergized and its mechanism is fully released. In the event the train continues uninterruptedly toward the highway crossing, the circuit of relay SR is successively opened at the circuit controlling elements of the successive train actuated devices, and operation of the signal S is continued uninterruptedly until the rear of the train passes the location of the last device A5 which is located close to the crossing, since the devices 30 are so spaced that relay TER is not energized long enough to open its back contact 3. When the rear of the train passes to the right of device A5 and contact 8 is closed, relay SR is energized over the circuit including the contacts 40 of the several train actuated devices and the check contact 11-12, and, upon picking up, closes its stick circuit at front contact 9. One path of the signal operating circuit is now open at back contact 2 of relay SR, but operation of the signal is continued by means of the path including back contact 3 of relay TER. With relay SR picked up the relay TER is energized and picks up to open back contact 3 at the expiration of its predetermined pick-up period and 50 which period I have assumed to be 5 seconds. Thus, operation of the signal S is stopped substantially 5 seconds subsequent to the rear of the train passing the device A5. As set forth hereinbefore, the train actuated devices of the 55 series are placed close enough together that a train moving at an appreciable speed passes from one device to the next in something less than 5 seconds. It follows that for all trains that do not stop along the section equipped 60 with the train actuated devices, the signal is operated continuously from the time the head end of the train encounters the first device A1 until substantially 5 seconds subsequent to the rear of the train passing the last device A5. 65

In the event a train should stop at any point along the control section, the circuit controlling elements 4 to 8, inclusive, all assume the closed condition in which they pass current and relay SR is picked up and relay TER is energized with 70 the result that operation of signal S ceases substantially 5 seconds after the train stops. As soon as the train resumes its movement, the circuit controlling element of the device in the vicinity of the train assumes the open or non-con- 75

ducting condition and relays SR and TER are released, and operation of the signal is restarted. Consequently, whenever a train stops along the control section, operation of the highway crossing signal ceases at the expiration of a predetermined period, and operation of the signal is restarted at once when the train again resumes its movement.

In Fig. 2, traffic normally moves over the track rails 1a and 1b in the direction indicated by an arrow, the rails are intersected by a highway H at which a signal S is located, and a series of train actuated devices is associated with the track rails the same as in Fig. 1. The control relay SR of Fig. 2 is likewise retained energized over a stick circuit that includes its own front contact 9 and the circuit controlling elements 4 to 8, inclusive, of the train actuated devices the same as in Fig. 1. In this form of the invention, the slow acting relay is a thermal relay TH having associated therewith two relays TPR and TSR. Normally, that is, when no train occupies the control section, the relay SR is energized over the stick circuit referred to above, relay TSR is energized over a stick circuit that includes its own front contact 15 and front contact 14 of relay SR, and relay TPR is energized over a simple circuit including check contact 16 of thermal relay TH.

When the head end of a train approaching the highway crossing encounters the train actuated devices A1 of Fig. 2, contact 4 assumes its open condition and control relay SR is released to close at its back contact 17 one path in the operating circuit for the signal S, and operation of the signal is initiated. Relay SR, upon releasing, opens front contact 14 interposed in the stick circuit for relay TSR and this latter relay is deenergized and releases to close at its back contact 18 a second branch path of the signal operating circuit. If this train continues without stopping, one or more of the circuit controlling elements of the train actuated devices are actuated at intervals less than the operating time of relay TH and operation of the signal S is continued without interruption until the rear of the train passes beyond the last device A5. When contact 8 of device A5 is closed, relay SR is picked up over a circuit that may be traced from the B terminal of the current source through the circuit controlling elements 4 to 8 of the train actuated devices, winding of relay SR, back contact 20 of relay TSR, front contact 21 of relay TPR, and to the opposite terminal C of the current source. With relay SR picked up and relay TSR down, current is supplied to the heater element 19 of thermal relay TH, the circuit including front contact 14 of relay SR, and back contact 22 of relay TSR. Check contact 16 of relay TH is at once opened subsequent to the heater element 19 being supplied with current, and relay TPR is released to open at its front contact 21 the pick-up circuit for relay SR and to close at its back contact 23 a third branch path in the signal operating circuit. Subsequent to the opening of check contact 16 and release of the relay TPR, control relay SR is retained energized over its stick circuit including front contact 9, which contact when closed completes, in effect, a shunt path around the check contact 16. Contact 24 of thermal relay TH is closed at the expiration of a predetermined period, say, for example, 5 seconds, and completes a pick-up circuit for relay TSR which circuit includes front contact 14

of relay SR, contact 24 of relay TH, and winding of relay TSR. Relay TSR at once picks up and is then retained energized over its front contact 15. The picking up of relay TSR to open back contact 22 interposed in the circuit for the heater element 19 causes relay TH to cool and reclose check contact 16 so that relay TPR is reenergized. With all three relays SR, TSR, and TPR restored to their normal energized conditions, all three branch paths of the signal operating circuit are opened and operation of the signal is stopped. It follows that when a train continues through the control section without stopping, the signal S is operated without interruption from the time the head end of the train encounters the first device A1 until the expiration of the operating time of the thermal relay TH, subsequent to the rear of the train passing to the right of the last device A5.

In case a train stops along the control section so that the contacts of the train actuated devices all assume the closed position, the relay SR is picked up and thermal relay TH is operated in the manner set forth above with the result that operation of the signal is discontinued at the end of the operating time of relay TH. A train having stopped and then again resuming its movement causes the circuit controlling element of the device in the vicinity of the train to assume its open position with the result that the relay SR is deenergized and operation of the signal is restarted.

In Fig. 3, the normal direction of traffic is that indicated by the arrow and the track rails to the left of the highway H are divided into two insulated track sections 1T and 2T, the section 2T being adjacent the highway. These sections 1T and 2T are each provided with the usual track circuit, which circuits include the track relays 1TR and 2TR, respectively. A series of train actuated devices A6, A7, and A8 is provided for the section 1T, the devices being spaced at selected points along the section. The initial device A6 of the series is preferably located not far from the entrance of the section, and the final device A8 is preferably located not far from the exit end of the section. Although only three devices are disclosed, it will be understood that the series may include any number and will include a sufficient number so that a train moving at a low speed will pass from one device to the next in something less than a predetermined period of time which may be 5 seconds. In practicing the invention, the section 1T would be extended to include points at which trains may ordinarily be required to stop, such as, for example, a passenger station or siding. The combined length of the two track sections 1T and 2T is sufficient to provide a desired minimum warning period of the highway crossing signal prior to the arrival of a train at the crossing when the train is travelling at the maximum speed for all trains.

Signal S of Fig. 3 is governed over the back contact 25 of a relay XR. Relay XR, in turn, is normally energized over a circuit including front contact 26 of track relay 1TR and front contact 27 of track relay 2TR. Relay XR is energized at times over an alternative circuit which may be traced from the B terminal of the current source over front contact 30 of control relay SR, front contact 29 of the associated slow pick-up relay TER, back contact 28 of track relay 1TR, front contact 27 of relay 2TR, winding 75

of relay XR and to the C terminal of the current source.

A train approaching the highway and entering track section 1T shunts track relay 1TR and that relay upon releasing opens the circuit for relay XR which in turn releases to close the operating circuit for the signal S, and the signal establishes a warning indication. Relay 1TR upon releasing also closes at its back contact 31 an energizing circuit for control relay SR, and that relay is at once picked up. This energizing circuit includes battery terminal B, circuit controlling elements 32, 33, and 79 of the train actuated devices A6, A7, and A8, respectively, back contact 31 of relay 1TR, winding of relay SR, check contact 11-12 of relay TER, and to the opposite terminal C of the current source. Relay SR on picking up closes at its front contact 34 a shunt path around the check contact 11-12 and completes at its front contact 30 an energizing circuit for the slow pick-up relay TER which relay is set into operation to close its contact 29 at the end of the predetermined pick-up period which preferably would be 5 seconds to agree with the spacing of the actuated devices referred to hereinbefore.

If the train advances at an appreciable speed, it reaches the first device A6 in less than the pick-up period of relay TER with the result that the contact 32 of device A6 is caused to assume its open position and relays SR and TER are de-energized. In the event the train proceeds without stopping through the section 1T, the relay SR is retained deenergized or at least is deenergized at intervals less than the pick-up period of relay TER and operation of the signal is continued without interruption. When the train enters the section 2T and shunts track relay 2TR, the relay XR is retained deenergized by virtue of front contact 27 of relay 2TR being open, and operation of the signal is continued until the train passes to the right of the highway crossing and vacates section 2T and relay 2TR is again picked up. In the event the train should stop while advancing through section 1T, the energizing circuit for relay SR is at once closed and that relay is picked up to initiate operation of the slow pick-up relay TER. With both relays SR and TER picked up, the alternative circuit for relay XR is completed with the result relay XR is picked up and the operation of the signal is stopped. When the train resumes its movement, the train actuated device in the vicinity of the train is influenced to cause the relay SR to be deenergized and operation of the signal is again started.

In Fig. 4, a stretch of railway track over which traffic normally moves in either direction is intersected by a highway H adjacent which a highway crossing signal S is located. This stretch of railway track is formed into two insulated track sections 3T and 4T, the junction of the two sections being located at the highway crossing. At the junction of sections 3T and 4T, the arrangement is such that the insulated rail joint 35 is placed in one rail to the left of the highway and the other insulated rail joint 36 is placed in the other rail to the right of the highway as will be readily understood by an inspection of Fig. 4. The track section 3T is provided with a track circuit which includes the left-hand magnet 37 of an interlocking relay IR, and the track section 4T is provided with a track circuit which includes the right-hand magnet 38 of the relay IR. A series of train actuated devices A9, A10, and A11

is associated with section 3T, and a second series of train actuated devices A12, A13, and A14 is associated with the track section 4T. Although only three devices are shown for each of these series, it will be understood that each series includes a sufficient number of devices that a train moving at an appreciable speed will advance from one device to the next in something less than a predetermined period of time which may be 5 seconds as assumed hereinbefore. An individual train actuated device A15 is associated with the track rails adjacent the intersection, that is, it is positioned at some point between the insulated rail joints 35 and 36 but in a position where highway traffic will not effectively influence the device. In this connection, it is to be recalled that track instruments of the type here contemplated are not readily responsive to vibrations transverse to the track rail. A control relay SR and an associated slow pick-up relay TER are provided for the apparatus of Fig. 4.

In describing the operation of the apparatus of Fig. 4, I shall first consider the case of a train approaching the highway crossing from the left. The train upon entering section 3T shunts magnet 37 of relay IR and that magnet is released to close its full down contacts 39, 40 and 41. With back contact 41 closed, the operating circuit for signal S is completed, and operation of the signal is initiated. The operating circuit for signal S includes the back contact 42 of relay SR and the back contact 43 of relay TER in parallel, and the back contact 41 of magnet 37 or back contact 56 of magnet 38 depending upon which of these magnets is released first. The closing of contact 40 of magnet 37 completes a circuit for control relay SR and which circuit starts from battery terminal B at the left-hand end of Fig. 4 and extends through the circuit controlling elements 44, 45, and 46 of the train actuated devices A9, A10, and A11, respectively, back contact 40, wire 41, front contact 48 of magnet 38, wire 49, circuit controlling element 50 of device A15, wire 51, winding of relay SR, check contact 11-12 of relay TER, and to terminal C. Relay SR on picking up completes at its front contact 52 a shunt path around check contact 11-12, and completes at front contact 63 an energizing circuit for relay TER. With relay SR picked up, one branch in the operating circuit of signal S is opened at back contact 42, but operation of the signal is continued over the branch path including back contact 43 of relay TER. In the event the train continues its movement, it causes the contact 44 of device A9 to open the circuit for relay SR and stop the operation of relay TER prior to the interval back contact 43 is opened, and hence operation of the signal is continued without interruption from the time the train enters section 3T until after the rear of the train passes to the right of the highway since the circuit for relay SR is retained open at the successive train actuated devices. When the head end of the train passes to the right of the insulated rail joint 36, the magnet 38 is deenergized but its back contacts 54, 55, and 56 are held open and its front contact 48 is held closed due to the interlocking feature of the relay.

It is to be noted that when the rear of the train is on the crossing the track circuit of section 3T is still shunted and magnet 37 is retained deenergized. This shunt path may be traced from the upper rail at the left of insulated rail joint 35 over wire 57, back contact 39, wire 58 to the upper rail at the right of insulated rail

joint 35, thence through the train wheels and axles to the lower rail. Consequently, operation of the signal S is continued until the rear of the train passes to the right of the highway crossing. 5 The train actuated device A15 being located at the crossing, relay SR is retained deenergized and relay TER made ineffective to stop the operation of the signal. In the event the train should stop at any point along the section 3T, then relay 10 SR is energized and the slow pick-up relay TER is operated with the result that operation of the signal S is discontinued at the expiration of the pick-up period of relay TER. As soon as the train 15 starts up again, the circuit for the relay SR is opened at the device in the vicinity of the train and operation of the signal is reestablished.

It is apparent that the operation of the apparatus of Fig. 4 in response to a train approaching the highway from the right through track section 20 4T is similar to that described in connection with a train approaching the highway crossing from the left, and it is thought that it need not be repeated.

Fig. 5 discloses apparatus for a train actuated device that may be used to interrupt the circuit for the control relay SR when a train is moving and to close the circuit when the train stops. The apparatus consists of a track circuit comprising a short insulated rail 59, a track battery 60 connected between rail 59 and the opposite rail 61, and the winding of a relay 62 connected between the rails 59 and 61. The insulated rail 59 is shorter than the distance between the two trucks 30 of the usual railway car. It follows that relay 62 is normally energized, is deenergized and released in response to the first truck wheel spanning the rails 59 and 61, and is momentarily picked up during the interval between the last wheel of the first truck of the car passing off rail 40 59 and the entrance of the leading wheel of the second truck passing onto rail 59. The control circuit for relay SR includes a front contact 63 and a back contact 64 of relay 62 in parallel. Consequently, as long as relay 62 is steadily energized, or is continuously deenergized, the circuit 45 for relay SR is closed, but a train moving over the rail 59 causes the circuit to be periodically interrupted. To check the normal position of relay 62 the front contact 65 may be interposed in a 50 wayside signal control circuit.

In Fig. 6, another possible arrangement for detecting movement of a train is disclosed. Here a track instrument A16 governs over its circuit controlling element 66 a relay 67, the front contact 55 68 and back contact 69 of which relay are interposed in parallel in the control circuit for relay SR.

Although I have described only certain forms of apparatus embodying my invention, it is understood that various changes and modifications may be made therein within the scope of the appended claims without departing from the spirit and scope of my invention.

Having thus described my invention, what I 65 claim is:

1. In combination, a stretch of railway track intersected by a highway, a highway crossing signal located at the intersection, a control relay, a slow acting relay having a contact arm which 70 is actuated in a predetermined interval, a series of train actuated devices spaced along the track rails for at least a portion of the stretch, said devices each including a circuit controlling element which is actuated to an open condition only when 75 a train is moving in the vicinity of the device,

circuit means for energizing the control relay and serially including the elements of the devices of the series, an operating circuit for the slow acting relay including a front contact of the control relay, and other circuit means for governing the operation of the signal and including said contact arm of the slow acting relay whereby operation of the signal is effected when a train moves uninterruptedly through the stretch of railway and is stopped at the end of said predetermined interval when the train stops along the stretch. 5 10

2. In combination, a stretch of railway track intersected by a highway, a highway crossing signal located at the intersection, a slow acting 15 relay having a contact arm which is actuated in a predetermined time interval, a series of train actuated devices spaced along the track rails for at least a portion of the stretch, said devices each including a circuit controlling element which is 20 actuated to an open condition only when a train is moving in the vicinity of the device, and said devices spaced sufficiently close together that a train moving at a given low speed will pass from one device to the next in substantially said predetermined time interval, circuit means for operating the slow acting relay and serially including the elements of said devices, and means for governing the operation of the signal including the contact arm of the relay. 25 30

3. In combination, a stretch of railway track intersected by a highway, a highway crossing signal located at the intersection, a slow pick-up relay having a predetermined pick-up period, a control relay, a series of train actuated devices 35 spaced along the track rails for at least a portion of the stretch, said devices each including a circuit controlling contact which is actuated to an open position only when a train is moving in the vicinity of the device, and said devices spaced sufficiently close together that a train moving at an appreciable speed passes from one device to the next in less than said predetermined pick-up period of the slow pick-up relay, a control circuit for the control relay including the contacts of 40 said devices in series, means including a front contact of the control relay to energize the slow pick-up relay, operating means governed by the control relay effective to operate the signal when the control relay is deenergized, and other operating means governed by the slow pick-up relay effective to operate the signal when the slow pick-up relay is deenergized. 45 50

4. In combination, a stretch of railway track intersected by a highway, a highway crossing signal located at the intersection, a slow pick-up relay having a predetermined pick-up period, a series of train actuated devices spaced along the track rails of the stretch with the nearest device adjacent the intersection and the most remote device a predetermined distance from the intersection, said devices spaced sufficiently close together that a train moving at a given low speed will pass from one device to the next in substantially said predetermined period, said devices each including a circuit controlling element which is 55 actuated to a non-conducting condition only when a train is moving in the vicinity of the device, circuit means to energize said slow pick-up relay and serially including the elements of said devices, and means for governing the operation of the signal including a contact of said relay. 60 65

5. In combination, a stretch of railway track intersected by a highway, a highway crossing signal located at the intersection, a control relay, a 70 75

slow pick-up relay having a predetermined pick-up period, a series of train actuated devices spaced along the track rails of the stretch with the nearest device adjacent the intersection and the most remote device a predetermined distance from the intersection, said devices spaced sufficiently close together that a train moving at a given low speed will pass from one device to the next in substantially said predetermined period, 10 said devices each including a circuit controlling element which is actuated to an open condition only when a train is moving in the vicinity of the device, a control circuit for the control relay serially including the elements of the devices, a 15 circuit for the slow pick-up relay including a front contact of the control relay, and circuit means for governing the signal controlled jointly by the control and slow pick-up relays.

6. In combination, a stretch of railway track 20 intersected by a highway, a highway crossing signal located at the intersection, a control relay, a slow pick-up relay having a predetermined pick-up period and including a check contact, a series of track instruments spaced along the 25 stretch with the first instrument a predetermined distance from the intersection and the last instrument adjacent the intersection, said instruments spaced sufficiently close together that a low speed train will move from one instrument to the 30 next in substantially said predetermined period, said instruments each including a contact which is opened at least momentarily by the vibration created in a track rail by a train moving past the instrument, circuit means for energizing said 35 control relay including the contacts of said instruments and said check contact, means including a front contact of the control relay to shunt around the check contact, an operating circuit for the slow pick-up relay including a front contact 40 of the control relay, and means for operating the signal including a contact of the slow pick-up relay.

7. In combination, a stretch of railway track over which traffic moves in either direction and 45 which is intersected by a highway, a highway crossing signal at the intersection, a slow pick-up relay having a predetermined pick-up period, two series of train actuated devices one on each 50 side of the crossing, said devices each including a circuit controlling element which assumes an open condition only when a train is moving in the vicinity of the device, the devices of each series spaced sufficiently close together that a train moving at an appreciable speed passes from one 55 device to the next in less than said predetermined pick-up period, two circuit means each effective to energize said relay and one serially including the circuit elements of the devices of one series and the other serially including the circuit elements of the devices of the other series, means controlled by a train to place the relay under the control of the circuit means associated with the direction in which the train approaches the crossing, and an operating circuit controlled by a train 60 approaching the crossing in either direction to operate the signal and including a back contact of said relay.

8. In combination, a stretch of railway track over which traffic moves in either direction and 70 which is intersected by a highway, a highway crossing signal at the intersection, a slow pick-up relay having a predetermined pick-up period, two series of train actuated devices one on each side of the crossing, said devices each including 75 a circuit controlling element which assumes an

open condition only when a train is moving in the vicinity of the device, the devices of each series spaced sufficiently close together that a train moving at an appreciable speed passes from one device to the next in less than said predetermined pick-up period, two circuit means each effective to energize said relay and one serially including the circuit elements of the devices of one series and the other serially including the circuit elements of the devices of the other series, means 10 controlled by a train to place the relay under the control of the circuit means associated with the direction in which the train approaches the crossing, an operating circuit controlled by a train approaching the crossing in either direction to 15 operate the signal and including a back contact of said relay, an individual train actuated device located adjacent the crossing, and means governed by said individual device when actuated by a train to render said two circuit means both in 20 effective to energize said relay.

9. In combination, a stretch of railway track over which traffic moves in either direction and which is intersected by a highway, a highway crossing signal at the intersection, a slow pick-up relay having a predetermined pick-up period, two series of train actuated devices one on each 25 side of the crossing, said devices each including a circuit controlling element which assumes an open condition only when a train is moving in the vicinity of the device, the devices of each series spaced sufficiently close together that a train moving at an appreciable speed passes from one device to the next in less than said predetermined pick-up period, two circuit means each effective 30 to energize said relay and one serially including the circuit elements of the devices of one series and the other serially including the circuit elements of the devices of the other series, means controlled by a train to place the relay under the control of the circuit means associated with the direction in which the train approaches the crossing, an operating circuit controlled by a train 35 approaching the crossing in either direction to operate the signal and including a back contact of said relay, and directional means controlled by a train travelling through the stretch operative to render each series of devices ineffective to control the relay when a train recedes from the 40 crossing.

10. In combination, a stretch of railway track over which traffic moves in either direction and which is intersected by a highway, a highway crossing signal at the intersection, said track formed into two insulated tracks sections one 55 on each side of the intersection and each provided with a track circuit including a magnet of an interlocking relay, two series of train actuated devices one associated with each section, said devices each including a circuit controlling element which assumes an open condition only when a train is moving in the vicinity of the device, and the devices of each series spaced along the associated section sufficiently close together that a train moving at an appreciable speed passes 60 from one to the next in less than a predetermined period, a slow pick-up relay having a pick-up period equal to said predetermined period, two circuit means each effective to energize the slow pick-up relay and each serially including the circuit elements of the devices of a particular series and a back contact of the interlocking relay magnet associated with the same section as the series, and an operating circuit for the signal including a back contact of the slow pick-up re- 70 75

lay in series with a back contact of each of interlocking relay magnets in parallel.

11. In combination, a stretch of railway track intersected by a highway, a highway crossing signal located at the intersection, a slow acting relay having a predetermined operating period, means controlled by said relay for at times operating said signal, a series of short insulated track sections spaced apart on one side of the intersection, said sections each characterized by being

shorter than the distance between the two trucks of a railway car, and said sections sufficiently close together that a train moving at an appreciable speed passes from one section to the next in less than said predetermined operating period, 5 a track circuit for each section including a track relay, and circuit means for operating said slow acting relay and including a front and a back contact in parallel of each relay of said sections.

HENRY S. YOUNG. 10
